UNITED STATES PATENT OFFICE

PAUL H. GRANGER, OF LOS ANGELES, CALIFORNIA

MEANS FOR DRAINING LIQUID FROM WELL TUBING

Application filed August 20, 1930. Serial No. 476,614.

This invention relates to a well tubing bleeder or means for draining liquid from well tubing, and the main object of the invention is to provide means whereby the liquid contained in an oil string or well tubing through which the oil or other liquid is pumped can be drained back into the well whenever desired, for example, when the string of tubing is to be raised out of the well or at any other time.

In the operation of wells such as deep oil wells, there is a column of liquid, generally of great height, extending upwardly from the working barrel to the top of the oil string or well tubing. In case it is necessary to withdraw the oil string from the well for any reason, this body of liquid is raised with the tubing, it being understood that under these conditions the standing valve at the bottom of the working barrel remains closed so that the oil is prevented from running out. In such withdrawal of the oil string from the well, it is customary to uncouple the tubing in stands of certain length and as each stand is uncoupled from the string, the oil contained in such stand runs out from the stand, flowing and spattering over the operating platform and surrounding parts, causing great inconvenience and considerable danger to the operators on account of the slippery nature of the oil. Moreover the oil contained in the tubing is lost and can not be recovered and put into tanks.

My invention provides for bleeding or draining off the oil or liquid from the oil string or well tubing before the same is elevated and removed from the well, thereby doing away with the difficulty above referred to.

In order to pull a wet string of tubing, the pulling equipment is subject to great strain due to added weight. This condition is removed by emptying the tubing before pulling.

In wells where perforated casing has not been set the present method of emptying the tubing has an hydraulic effect on the formation often causing it to cave or so disturb the sediment that same remains in suspension and therefore comes in direct communication

with the pump causing excessive wear and necessitating ultimate renewal of working parts. My present invention also does away with these injurious results.

Another application of my invention is in connection with flushing out the well tubing when necessary. Sand often accumulates around the standing valve and holds the ball of same off its seat. My invention provides for temporarily opening the standing valve so as to permit oil to rush past the same and clear it of sand.

This device is also useful when a pump becomes gas bound, that is, the chamber becomes filled with gas under pressure. At this time oil cannot enter the pump until the height of fluid rises above the pump to a point where the weight is great enough to lift the standing valve ball. It is frequently the case that the well does not have a natural fluid level of sufficient height to lift the standing valve ball. It then becomes necessary to empty the working barrel, and my invention provides for such operation.

An important object of the invention is to provide for release of the valve opening means, so as to allow the valve to return to closed position under certain conditions as hereinafter explained.

The accompanying drawings illustrate embodiments of my invention and referring thereto:

Fig. 1 is a vertical section of the tubing bleeder in normal position.

Fig. 2 is a similar view showing the device in operated position.

Fig. 3 is an enlarged section of the catch means used to control the operation of the bleeder, the same being shown in position corresponding to that of Fig. 1.

Fig. 4 is a view similar to Fig. 3 showing the parts in position corresponding to that of Fig. 2.

Fig. 5 is a side elevation of the means shown in Fig. 3.

Fig. 6 is a section on line 6—6 in Fig. 5.

Fig. 7 is a section on line 7—7 in Fig. 4.

Fig. 8 is a section on line 8—8 in Fig. 4.

Fig. 9 is an elevation of the portion of the device shown in Fig. 8.

Fig. 10 is a vertical section showing a modification of the means for releasing the valve operating means.

Fig. 11 is a partial section of a modified arrangement of the gas separating means.

The tubing bleeder constituting my invention is adapted and intended to be attached to the lower end of a working barrel, such as indicated at 1 in Figs. 1 and 2, said working barrel having the usual standing valve 2 at its lower end controlling the entry of liquid thereinto. Attached to the lower end of the working barrel 1, for example, by means of a collar 3, is a perforated section 4 of tubing, through which the oil or liquid to be pumped passes from the well bore to the standing valve. A pipe section 5 is preferably mounted on the lower end of tubing section 4, and extends upwardly around the same, leaving a space 6 between members 4 and 5, communicating through openings 5' at the top of pipe section 5 (see Figs. 8 and 9) with the space around the well tubing. The perforations 4' in tubing section 4 are preferably limited to the lower portion of said section, so that the oil entering through openings 5' passes downwardly in space 6 before it reaches the inlet perforations 4'. The member 5 acts as a gas trap or so-called "gas anchor" as gases contained in the oil are separated therefrom as it passes downwardly in space 6, and the oil is delivered to the well tubing sufficiently free from gas to prevent interference with proper operation of the pumping means.

Means are provided for lifting the standing valve when it is desired to drain the well tubing. Said means comprises a stem 8' on a rod 8 said stem extending within tubing section 4 and within the seat of standing valve 2 so as to engage the ball or movable member of said valve, said rod 8 being connected by cross pin 9 to a collar 10 in which is secured a tube 11 extending to, or nearly to the bottom of the well. Secured to tubing section 4 by a collar 12 is a length of tubing 13 which extends within the tubing 11 and is adapted to extend nearly to the bottom of the well when the working barrel is in operating position, said tubing 13 having slots 14 through which the cross pin 9 extends. Means are mounted on said rod 8 and within the member 4 for clutching or connecting the said rod to said member 4 under certain conditions as hereinafter set forth. Said clutch means for connecting the rod 8 with the tube 4 may comprise a base member 15 mounted between members 4 and 12 and having an opening 16 through which the rod 8 may slide, said member 15 having secured thereon or formed therewith, bearing means 18 extending upwardly on opposite sides of the rod 8 and formed respectively with horizontal slots 19 in which slide dogs or clutch members 20, the inner ends of which are adapted to en-

gage under certain conditions under shoulder 21 on the rod 8.

A movable clutch member 24 is mounted to slide on the rod 8 by means of opening 25 on said member 24, and has secured thereto and formed thereon downwardly extending projections 27 provided with inclined faces 28 on the inside thereof adapted to engage the outer ends of the respective sliding dogs 20 to force the same inwardly, the said outer ends of said sliding dogs being preferably inclined or tapered in correspondence with the inclination of the operating faces 28 so as to provide an effective bearing for engagement therewith. The movable clutch member 24 is normally held in elevated position relative to the clutch member 15 by means of springs 35 interposed between said clutch members, said springs surrounding and being supported by bolts 36 which are secured to the member 15 and pass through openings in the upper member 24. Nuts 37 on said bolts engage the upper clutch member 24 to limit the upward movement thereof.

I prefer to so construct the device that, if desired, the catch means above described can be returned to normal position so as to allow the standing valve to be reseated. For this purpose springs 31 may be mounted on the members 18 and engage the dogs 20 to force the same outwardly and the operating rod 8 may be provided with inclined or flaring portion 17 beneath the shoulder 21 adapted to engage the inner ends of the dogs 20 on upward movement of the member 8 so as to force said dogs outwardly. Passages 32 are preferably provided in the member 15, said passages being for example adjacent the operating rod 8 and being normally closed by flaps 33' carried by leaf springs 33 mounted on member 15, these flaps tending to open on down-rush of oil so as to clear any sand which may lodge on top of the clutch means, but being normally closed to prevent escape of gas into the oil contained in tube 4.

The perforations indicated at 4' in the tube section 4 are preferably confined to the lower portion of said tubing section so that an unperforated portion thereof is provided within the gas trap tube 5 throughout a sufficient height to insure release of gas from oil before it enters said perforations. Said perforations are also preferably at a level adjacent the level of the clutch member 24. The movable catch member above described is operated downwardly under certain conditions by the force of liquid descending through the standing valve and the tubing section 4 and issuing through the perforations 4', and in order to insure effective operation the tubing section 4 is preferably provided with a contracted portion 30 above and adjacent the perforations 4' and the clutch member 24 so as to contract the stream of flow and cause it to impinge with sufficiently

high velocity on the clutch member 24 to operate the same.

The operation of the device is as follows: The oil string and working barrel are lowered into the well with the parts above described attached thereto, and when the bottom of the tube 11 reaches the bottom of the well it arrests the further down movement of said tube and of rod 8 connected thereto, and further lowering of the oil string and working barrel will cause the standing valve 2 to be opened by relative upward movement of said rod. It will, therefore, be understood that the oil string and the parts supported thereby will normally be raised somewhat so that the rod 8 and the parts connected thereto are allowed to descend under the action of gravity and the parts are allowed to assume the position shown in Figs. 1 and 3, the standing valve being therefore normally permitted to close. The oil string can be raised or lowered as often as desired without operating the clutch means above described, provided that the level of the liquid within the well outside the oil string, this being the normal condition before the pump is set in operation. When the working barrel has been put into operation and the oil string or string of tubing has been filled with oil or liquid in the normal pumping operation and it is desired to remove the oil string or string of tubing from the well, the said string is first lowered so as to bring the means 11 in contact with the bottom of the well and in the ensuing downward movement of the string of tubing to cause the parts to move to the position shown in Figs. 2 and 4.

In moving to such elevated position relative to the well tubing, the tube 11 operates through pin 9, rod 8 and stem 8' to raise the movable member or ball of the standing valve as shown in Fig. 2, thereby opening the standing valve and allowing the liquid in the oil string or string of tubing to flow down rapidly past the standing valve and out through the perforated section 4. This rapid downward flow of the liquid and the deflection thereof outwardly from the tubing causes downward pressure on the operating member 4 of the clutch means, causing said clutch member to move downwardly against the resistance of the springs 35 and bringing the inclined faces 28 in engagement with the outer ends of the dogs or catch means 20 so as to force the latter inwardly to the position shown in Fig. 4, so that their inner ends engage under the shoulders 21 on the rod 8, and hold said rod in position to retain the standing valve in open position and permit free drainage of liquid from the tubing therethrough. The oil string may then be withdrawn from the well, being elevated and uncoupled a stand at a time, without any efflux of oil or liquid

from the respective stands as they are being uncoupled or removed.

When the device is used only for emptying the well tubing preparatory to, or during, removal of the tubing from the well, the clutch means may be released manually, after the working barrel has been withdrawn from the well and the device opened up. I may, however, provide means for automatically releasing the catch means upon cessation of downflow of liquid from the well tubing. Such means may comprise the springs 31, which tend to press the dogs or catches 20 outwardly so that when the downward pressure on the member 24 ceases by reason of the cessation of oil-flow, due to emptying of the well tubing either wholly, or sufficiently to equalize the levels within and without the tubing, the dogs 20 will move outward and release the rod 8, which then falls to normal position.

In case oil is to be drawn from the tubing, for flushing out sand from the standing valve, it is only necessary to lower the tubing as aforesaid to cause engagement of the member 13 with the bottom of the well and thereby open the standing valve by operation of rod 8. Oil will then flow from the well tubing until equality of level is established inside and outside of the tubing, whereupon the rod is released and returned to normal position, closing the standing valve, as above explained. To ensure this releasing operation under these conditions, I prefer to provide the inclined portion 17 on rod 8 which can be made to operate the dogs 20 (by pressing on springs 31, or by direct engagement) to force the same outward, by lowering the well tubing somewhat farther than the position shown in Figs. 2 and 4, causing said inclined portion to move upwardly from the position of Fig. 4 and to push dogs 20 out of engagement with shoulders 21. This operation will, of course, only take place after the clutch faces 28 have been moved upward on completion of the flushing operation.

If it is desired to empty the working barrel to remove gas therefrom, the well tubing is first lowered to open the standing valve as above described and is then raised sufficiently to release all the oil and gas from the working barrel. The catch rod 8 is then released by operation of inclined portion 17, the tubing being lowered, for that purpose, sufficiently to effect such operation by engagement of member 11 with the bottom of the well, and being then raised to allow the parts to resume normal position.

The springs 31 facilitate the operation of the catch releasing means, but they may be omitted if desired, as shown in Fig. 10, the inclined or flaring portion 17 engaging directly with the catch dogs indicated at 20.

As shown in Fig. 11, the gas trap means

may be mounted on the member, indicated at 40, which slides on the well tubing to release the standing valve. In this figure a tube 41 is screwed on the collar 42, mounted on the upper end of member 40, and extends upwardly around the perforated well tubing section 44 secured by collar 45 to the lower end of working barrel 46. The upper end portion of tube 41 is formed with apertures 47 for admission to slide on the tubing section 44, as the member 41 moves upwardly in the valve opening operation. The construction and operation is otherwise the same as in the form shown in Fig. 1. In this case the gas trap sleeve or tube is movably mounted on the perforated section, instead of being fixedly mounted thereon, but the effect is the same as regards its function in separating gas.

I claim:

1. A draining means for well tubing comprising a perforated tubular means adapted for attachment to the working barrel at the lower end of such well tubing, a valve operating member provided with a shoulder vertically movable in said tubular means and adapted to engage and lift the movable member of the standing valve of the working barrel so as to open said valve, a guide means connected to and extending downwardly from said perforated tubular means, a tube surrounding said guide means and connected to said valve operating member and adapted to be arrested by its engagement at the bottom of the well, to lift the valve operating member so as to open the standing valve, a clutch member mounted within said tubular member and provided with dogs adapted to engage the aforesaid shoulder on said valve operating member, and a clutch operating member mounted to slide vertically within said tubular member and adapted to operate said dogs to move same into engagement to said shoulders, said clutch operating means being adapted to be operated by the downflow of liquid past the standing valve when said standing valve is open, such downflow of liquid being due to difference in level of the liquid within and outside of the tubing.

2. Means for opening the standing valve of a well pump working barrel, comprising supporting means mounted on the working barrel, valve operating means mounted to move vertically on said supporting means, means connected to said valve operating means and adapted to engage the bottom of the well and on such engagement to move the valve operating means to open the standing valve, catch means for holding the valve operating means in position to open the standing valve, means responsive to outflow of liquid from the standing valve to operate said catch means, and means for releasing the catch means from the valve operating

means on cessation of outflow of liquid from the standing valve.

3. Means for opening the standing valve of a well pump working barrel comprising supporting means mounted on the working barrel, valve operating means mounted to move vertically on said supporting means, and provided with a shoulder, means connected to said valve operating means and adapted to engage the bottom of the well, and on such engagement to move the valve operating means so as to open the standing valve, catch means adapted to engage said shoulder on the valve operating means to hold the valve operating means in position to hold the standing valve open, means responsive to outflow of liquid from the standing valve to operate the catch means to position to hold the standing valve open, and incline means on the valve operating means adapted to engage said catch means to release it from said shoulder on the valve operating means.

In testimony whereof I have hereunto subscribed my name this 30 day of July, 1930.

PAUL H. GRANGER.
